UNITED STATES PATENT OFFICE.

MAX DI JULIO, OF PHILADELPHIA, PENNSYLVANIA.

DESIGN FOR A SESQUICENTENNIAL PLAQUE.

Application filed November 18, 1925. Serial No. 15,447. Term of patent 3½ years.

To all whom it may concern:

Be it known that I, MAX DI JULIO, a citizen of the United States of America, residing at Philadelphia, in the county of Philadelphia and State of Pennsylvania, have invented a new, original, and ornamental Design for a Sesquicentennial Plaque, of which the following is a specification, reference being had to the accompanying drawing, forming a part thereof.

Figure 1 is a front elevation of the plaque.

Figure 2 is a top edge view of the plaque.

I claim:—

The ornamental design for a sesquicentennial plaque, as shown.

MAX DI JULIO.
